No. 851,955.

PATENTED APR. 30, 1907.

I. N. MORFORD.
WIRE FENCE MACHINE.
APPLICATION FILED AUG. 14, 1906.

UNITED STATES PATENT OFFICE.

ISAAC N. MORFORD, OF WAYNESVILLE, ILLINOIS.

WIRE-FENCE MACHINE.

No. 851,955.

Specification of Letters Patent.

Patented April 30, 1907.

Application filed August 14, 1906. Serial No. 330,608.

To all whom it may concern:

Be it known that I, ISAAC N. MORFORD, a citizen of the United States, residing at Waynesville, in the county of DeWitt and State of Illinois, have invented a new and useful Wire-Fence Machine, of which the following is a specification.

The invention relates to improvements in wire fence machines.

10 The object of the present invention is to simplify and improve the construction of wire fence machines, more especially that shown and described in Patent No. 821,112, granted to me May 22, 1906, and to enable the 15 same to have a more substantial and direct hold on the top and bottom wires of a fence.

A further object of the invention is to provide a wire fence machine of this character, which will be capable of adjustment to suit 20 any conditions of ground, so that the wire stays will be perfectly plumb, even when the ground is not level.

With these and other objects in view, the invention consists in the construction and 25 novel combination of parts hereinafter fully described, illustrated in the accompanying drawing, and pointed out in the claims here-to appended; it being understood that various changes in the form, proportion, size and 30 minor details of construction, within the scope of the claims, may be resorted to without departing from the spirit or sacrificing any of the advantages of the invention.

In the drawing:—Figure 1 is a side elevation of a wire fence machine, constructed in accordance with this invention and shown applied to a fence. Fig. 2 is a similar view, showing the opposite side of the wire fence machine. Fig. 3 is a detail perspective view 40 of one of the cross heads of the machine. Fig. 4 is a detail view of the wire twisting tool.

Like numerals of reference designate corresponding parts in all the figures of the drawing.

1 and 2 designate standards or uprights, consisting of rods and connected adjacent to their lower and upper ends by adjustable cross heads 3, consisting of castings and secured to the standards or uprights 1 and 2 by set screws 4, or other suitable fastening devices. The cross heads, which are of double semi-circular shape, are disposed horizontally, and have curved sides and are provided with 55 an intermediate centrally arranged arm or portion 5, cast integral with the cross heads,

and terminating in a forked catch or portion 6. The forked portions or catches 6 are adapted to straddle a stay 7 at the upper and lower ends thereof, and they are arranged to engage the top and bottom line wires 8 and 9 of the fence, and are interposed between the same to prevent the said top and bottom wires 8 and 9 from being drawn toward each other by the twisting of the stay. The sides 65 of the cross piece terminate in eyes 10, which adjustably receive the uprights or standards, and which are adapted to slide on the same to enable the cross heads to be positioned properly with relation to the top and bottom 70 wires of the fence.

The standard or upright 1 is provided at intervals with hooks 11 for engaging the line wires of the fence, as clearly shown in Fig. 2 of the drawing, and these hooks assist in holding the machine in engagement with the fence. The machine is adjustably secured to the fence by means of a relatively fixed horizontally disposed U-shaped bar or member 12, and a pivoted arm or member 13, which is adjustably secured at an intermediate point to the U-shaped bar or member, and which is provided at its outer end with terminal means for engaging one of the line wires of the fence. The U-shaped bar or member 80 consists of upper and lower horizontal portions secured at their inner ends to the standard or upright 1, and connected at their outer portions by an arcuate portion 14, which is provided with an arcuate slot 15. 90 The arm or member 13 is secured at its inner end by a pivot 16 to the standard or upright 1, and it extends beyond the arcuate portion of the U-shaped bar or member. The said arm or member 13 is provided at an intermediate point with a longitudinal slot 17, which extends in advance and in rear of the arcuate portion of the U-shaped bar or member. The bar or member 12 is adjustably secured to the bar or arm 13 by means of a bolt 100 18, or other suitable fastening device, which is arranged in the slots 15 and 17 and which permits the machine to be adjusted to a perpendicular position, when constructing a fence on a hill side, or on other uneven ground. 105 By this construction, the machine may be adjusted to suit any character of ground, so that the stays will be perfectly plumb or vertical. The pivoted arm or member is provided at its outer end with a terminal fork 19 110 for engaging the wire 20, which is retained in engagement with the fork by a pivoted latch

21, both of which parts are constructed the same as those shown and described in the said patent.

The machine is operated the same as that shown and described in the said patent. Two stay wires are arranged at opposite sides of the line wires, and secured to the top and bottom line wires of the fence by twisting them around the same. The wires of the stay are then twisted between each of the line wires by means of a twisting tool 22, consisting of a central body portion and opposite arms 25. The body portion is provided with a centrally arranged slot 24, extending inwardly from one of the side edges of the tool to the center thereof. The arms 23 are provided with openings 25, which enable the tool to be readily grasped and operated. The tool is of a length to rotate between the upper rights or standards 1 and 2.

Having thus fully described my invention, what I claim as new and desire to secure by Letters Patent, is:—

1. A wire fence machine comprising a pair of standards, means carried by one of the standards for engaging the fence wires, and horizontal cross heads disposed transversely of the fence and extending from one side thereof and composed of opposite sides connected with the standards, and a central integral arm connected with the said sides and provided with a terminal fork arranged to

engage a stay and adapted also to engage the top and bottom wires of the fence to prevent the same from being drawn together by the twisting of the stay.

2. A wire fence machine comprising a pair of standards, and horizontally disposed substantially double semi-circular cross heads arranged horizontally and extending laterally from one side of the fence and composed of opposite sides secured to the standards, and a central arm having terminal means for engaging a stay and a line wire of a fence.

3. A wire fence machine, comprising a pair of standards, means for connecting the same, a substantially U-shaped bar or member having an arcuate portion and secured to one of the standards, a pivoted arm mounted on such standard and crossing the arcuate portion of the said bar or member, the said arcuate portion and the arm being provided with intersecting slots, a fastening device arranged in the intersecting slots for adjustably securing the arm to the said arcuate portion, and terminal means carried by the arm for engaging the fence.

In testimony, that I claim the foregoing as my own, I have hereto affixed my signature in the presence of two witnesses.

ISAAC N. MORFORD.
